CHARLES S. WOLFE, OF NORRISTOWN, PENNSYLVANIA, ASSIGNOR TO BURD P. EVANS,
OF TRAPPE, PENNSYLVANIA

STATIC SUPPRESSOR

Application filed May 10, 1930. Serial No. 451,415.

My invention relates to a system for suppressing or reducing the effects of static impulses or similar disturbances upon radio receiving apparatus.

5 An object of my invention is to devise a system which may be incorporated in the audio frequency circuit of a radio receiving apparatus for effectively reducing the effects of interfering currents due to static and other impulses.

10 A further object of my invention is to devise a static suppressor arrangement which may be manufactured and sold as an independent unit and inserted between existing 15 radio sets and their loud speakers.

In accomplishing the objects of my invention I employ a special transformer connected in the audio frequency output circuit of a radio receiving apparatus, the transformer 20 having two secondary windings, one of which is connected directly to the reproducing apparatus or loud speaker, and the other connected to the reproducer through a trigger-like element in opposing relation to the first 25 secondary winding.

During normal operation, the trigger-like element possesses high internal resistance, and substantially no current is supplied to the loud speaker by the second secondary 30 winding. Upon the receipt of a static or other impulse superimposed upon the normal signal strength, the resistance of the trigger-like element automatically reduces and permits the flow of current from the second secondary to oppose the current supplied by the first secondary winding.

35 My invention is illustrated in the accompanying drawing in which:

Figure 1 is a circuit diagram illustrating 40 one form of the invention, and

Figure 2 is a circuit diagram illustrating 45 a second form of the invention.

Referring to Figure 1, 1 indicates a radio receiving apparatus which may comprise 50 known types of radio receivers including the usual amplifying and detecting apparatus. To the low frequency output circuit of receiver 1 is connected a transformer 2 having a primary winding 3 and two secondary 55 windings 4 and 5. Transformer 2 is pref-

erably provided with an iron core and so designed that the magnetic leakage is reduced to a minimum. Secondary windings 4 and 5 are also preferably wound in bifilar fashion in order that they shall be substantially identical in every respect. Winding 4 is connected directly to a loud speaker 6 or other reproducing apparatus by wires 4a and 4b. The beginning of secondary winding 5 is connected to the end of secondary winding 4 by 60 connection 5a, and the end of secondary winding 5 is connected to beginning of winding 4 through a trigger-like element represented within the dotted square 7. It will thus be seen that windings 4 and 5 are connected in 65 opposing relation to the loud speaker 6 with the trigger-like element 7 interposed in the connection between the loud speaker and secondary winding 5.

The trigger-like element 7 is a device which 70 possesses high internal resistance for applied voltages up to certain value, and above this value the internal resistance automatically reduces and permits the flow of current. Various devices possessing this characteristic 75 may be incorporated in my system; it being essential, however, that the device have this characteristic in both directions. I have obtained good results with a variable carbon contact resistance, and also with a variable 80 water rheostat resistance. In Figure 1 I have diagrammatically illustrated a combination of devices which I have also found to give good results. In the combination shown in the dotted square, 7a indicates a variable 85 carbon contact resistance connected in series circuit relation with two neon lamps 7b. The neon lamps are normally energized from a source of current 7c, which may be either a source of direct current or a source of alternating current. Choke coils (or resistances) 7d may be inserted between the source 7c and the lamps 7b to prevent the source 7c from shunting current around the lamps 7b from the secondary winding 5. As indicated 90 above, satisfactory operation may be obtained by employing carbon contact resistance 7a alone, or by employing the neon lamp arrangement alone. It is understood that only one neon lamp may be used instead of 100

two as shown, or two or more lamps may be connected in parallel.

Operation of Figure 1 is as follows: The current supplied to the neon lamps 7b is adjusted until the lamps are operating just at the critical point at which the internal resistance is very high, but upon the application of additional potential across the terminals, the internal resistance drops and permits the flow of current through the lamp. Under normal operation, therefore, the signal strength is not sufficient to lower the internal resistance of the lamps 7b and to permit substantial current to be supplied by this winding; the loud speaker being operated substantially entirely from winding 4. Upon the receipt of a disturbing impulse, however, the internal resistance of lamp 7b is reduced, and winding 5 is thereby effectively connected in parallel in opposing relation with winding 4, and the impulse in one winding opposes the impulse in the other. After the passage of the impulse, the normal resistance conditions are restored, and the loud speaker continues to operate on the winding 4. Since the trigger-device 7 has the same characteristic in both directions, the arrangement will operate effectively to prevent disturbances in the loud speaker by impulses of either polarity.

In addition to the devices mentioned above, certain electrolytic cells are known to possess the bi-lateral trigger-like conduction characteristic necessary for the operation of my invention, and such devices may be employed if desired.

In Figure 2 I have illustrated a modified form of my invention in which the circuit of secondary winding 5 normally remains open, and is closed by relay 8 controlled by photoelectric cell 9, which in turn is controlled by incandescent lamp 10 connected in series with the primary winding 3. The lamp 10 is preferably filled with neon gas, and will produce a glow when energized to a definite degree. An amplifier 11 is inserted between photoelectric cell 9 and the relay 8 to amplify the feeble current generated in the cell circuit.

Operation of Figure 2 is as follows: Under operation with normal signal strength, the effect of lamp 10 upon cell 9 is not sufficient to operate relay 8. Upon the receipt of a disturbing impulse superimposed upon the normal signal, lamp 10 will glow brighter and thereby increase the current generated in the cell circuit and cause the operation of relay 8. Secondary winding 5 will therefore, be connected in parallel with winding 4 in opposing relation to effectively prevent a disturbance by the impulse upon the loud speaker. After the impulse has passed, the circuits will be restored to their normal condition and winding 5 disconnected from the loud speaker.

It will be understood by one skilled in the art that the two circuits from the secondary winding to the loud speaker must be bal-

anced, and for this purpose, adjustable resistances or impedances may be inserted in one or both circuits for the purpose of obtaining a proper balance. In order to obtain effective neutralization of the impulse, the two circuits must transmit impulse currents substantially 180 degrees out of phase and of substantially the same amplitude. I find that it is easier to obtain a balance by employing non-inductive resistance elements in the circuits.

While I have described my invention as applied to a radio receiver for suppressing disturbances due to static and other impulses, it is apparent that the device may be used at the receiving end of a telephone or telegraph line for suppressing disturbances due to current or voltage impulses of whatever origin. It is also to be understood that while I have illustrated and explained my invention in co-operation with a loud speaker, the invention is not limited in its application to any particular form of translating device.

It is not essential that the trigger-like device be perfect in its operation, that is, that it possess infinite resistance up to a certain voltage and then very low resistance above that voltage, but it will be understood that a certain current may flow through the device under normal signal strength operation but not of sufficient value to substantially reduce the signal strength at the loud speaker.

What I claim is:

1. An impulse suppressor comprising input and output terminals, a transformer having a primary winding connected to said input terminals, a secondary winding connected to said output terminals, a second secondary winding connected to said output terminals in opposing relation to the first and having in series therewith a bi-lateral conductor element of fixed physical dimensions, said element having normally high resistance and being characterized by a substantial reduction in resistance upon the application of voltage above a certain value, and electric means for varying the break down voltage of said element.

2. In a signaling system, the combination of a circuit for collecting signal current subject to disturbing impulses, a signal translating device, a transformer connected to said collecting circuit and having two secondary windings, two circuits connecting said windings to said device in opposing relation, a gaseous discharge device connected in series in one of said circuits, and means including an auxiliary source of current to so energize said discharge device that normal signal currents are not substantially transmitted by said circuit, but abnormal impulses render said device effective to transmit current through said circuit.

3. In a signaling system, the combination of a circuit for collecting signal current sub-

ject to disturbing impulses, a detector connected to said collector circuit, a transformer connected to said detector for receiving detected low frequency signals, said transformer having two secondary windings, a signal translating device connected to one of said secondary windings, said second secondary winding being connected to said translating device in opposed relation to said first secondary winding, a normally non-conductive gaseous discharge device connected in series with the circuit of one of said secondary windings, and means for normally biasing said discharge device to a critical condition whereby the application of a potential above critical value renders the discharge device substantially conductive.

4. In a signaling system, the combination of a circuit for collecting signal current subject to disturbing impulses, a detector connected to said collector circuit, a transformer connected to said detector for receiving detected low frequency signals, said transformer having two secondary windings, a signal translating device connected to one of said secondary windings, said second secondary winding being connected to said translating device in opposed relation to said first secondary winding, a normally non-conductive gaseous discharge device connected in series with the circuit of one of said secondary windings, said discharge device comprising an evacuated envelope containing a pair of spaced electrodes in the gaseous atmosphere, and an adjustable source of current connected across said electrodes for normally biasing said discharge device to a critical condition whereby the application of a potential above a critical value renders the discharge device substantially conductive.

40 In witness whereof I affix my signature.
CHARLES S. WOLFE.
